UNITED STATES PATENT OFFICE.

CHARLES HENRY FAAS, OF PORTLAND, OREGON.

DESIGN FOR AN EMBLEM OR BADGE.

No. 38,714.

Specification for Design.

Patented Aug. 6, 1907.

Application filed June 15, 1907. Serial No. 379,287. Term of patent 3½ years.

To all whom it may concern:

Be it known that I, CHARLES HENRY FAAS, a citizen of the United States, residing at Portland, in the county of Multnomah and State of Oregon, have invented a new, original, and ornamental Design for Emblem or Badge, of which the following is a specification, reference being had to the accompanying drawing, forming part thereof.

The figure of the drawing is a view showing the emblem or badge.

I claim:

The ornamental design for emblem or badge as shown.

CHARLES HENRY FAAS.
